CONCESSION STAND

Warren C. Kiser and Chesley E. Lennon, Jr.,
Longview, Tex.

Application August 20, 1949, Serial No. 4,622

Term of patent 3½ years

(Cl. D13—1)

To all whom it may concern:

Be it known that we, Warren C. Kiser and Chesley E. Lennon, Jr., citizens of the United States, residing at Longview, in the county of Gregg and State of Texas, have invented a new, original, and ornamental Design for a Concession Stand, of which the following is a specification, reference being had to the accompanying drawing, forming a part thereof.

In the drawing:

Fig. 1 is a side elevation of a concession stand showing our new design.

Fig. 2 is an elevational view of another side thereof.

The two sides of the stand not shown, are substantially similar to the side shown in Fig. 2.

We claim:

The ornamental design for a concession stand, as shown and described.

WARREN C. KISER.
CHESLEY E. LENNON, JR.
